Primary Examiner—Lucy Lieberman

(57) CLAIM

The ornamental design for a parking timer reminding device, as shown and described.

DESCRIPTION

FIG. 1 is a front elevation view of a parking timer reminding device showing my new design;

FIG. 2 is a rear elevation view thereof;

FIG. 3 is a left side elevation thereof;

FIG. 4 is a right side elevation thereof;

FIG. 5 is a top plan view thereof, the bottom plan view is a mirror image thereto; and,

FIG. 6 is a perspective view thereof.
